UNITED STATES PATENT OFFICE.

PERCY D. SHIRLEY, OF ST. PAUL, MINNESOTA.

ENGRAVING-BLOCK.

1,242,993.

Specification of Letters Patent.

Patented Oct. 16, 1917.

Application filed May 1, 1917. Serial No. 165,661.

To all whom it may concern:

Be it known that I, PERCY D. SHIRLEY, a citizen of the United States, and a resident of the city of St. Paul, county of Ramsey, 5 and State of Minnesota, have invented a certain new and useful Improvement in Engraving-Blocks, of which the following is a specification.

This invention relates to a jeweler's engraving block and has for its object to provide an improved device of this character. The engraving blocks in use at the present time, after a short duration of use, have a tendency to develop lateral or "side play" 10 between their upper and lower halves. The object of my invention therefore is to provide means for minimizing friction and wear between the movable parts of the block and preventing this undesirable lateral 15 movement caused by wear of these parts and which generally occurs after the block 20 has been in use for a short time.

With these objects in view, I have devised the combination of parts hereinafter set 25 forth and more particularly pointed out in the claims appended hereto.

For a more particular description of my invention, reference is to be had to the accompanying drawings, forming part hereof, 30 in which;

Figure 1 is a vertical sectional view of an engraving block showing my improvements,

Fig. 2 is a plan view of the ball bearing which is interposed between the halves of 35 the block; and

Fig. 3 is a sectional view on the line 3—3 of Fig. 2, looking in the direction of the arrows.

Throughout the various views of the 40 drawing similar reference characters designate similar parts.

In the preferred embodiment of my invention as illustrated in the accompanying drawing, 1 indicates the usual semi-spherical lower half of the engraving block and 2 indicates the upper half which carries the jaws of the device and which is adapted to rest upon the lower half 1. The lower half 1 is provided with a central recess 3 into 45 which extends a central stud or spindle 4 formed on the upper half 2 of the block. The upper half of the block has its under surface cut away or depressed as at 5 and

the lower half has its upper surface correspondingly recessed as at 6 and these two depressions 5 and 6 form between them a space for the ball bearing, to be described. 55

The ball bearing which is interposed between the halves of the block to minimize friction therebetween, has a central bushing 60 7 having an opening 8 through which the spindle 4 extends, as shown.

A pair of spaced-apart plates or disks 9 are utilized to hold the balls 10, and these plates are held in spaced-apart relationship by the bushing 7 which has the shoulders 11 extending between the plates or disks 9. The edges of the faces on the bushing 7 are riveted as at 12 to secure the bushing to the plates and to securely hold the plates in 70 position. The plates 9 are provided with a plurality of perforations 13 through which portions of the balls project and bear against the surfaces of the depressions 5 and 6. 75

Apertures 14 are provided in the plates 9 through which a locking pin or screw, commonly used in engraving blocks, may pass, to lock the upper and lower halves of the block together.

It will be seen that I have provided a device having a minimum of parts and which is readily demountable when desired. The depressions as at 5 and 6 allow the two halves of the block to come very close together at their edges which prevents grease from the 85 balls working out on the hands of the workman and also prevents dirt and gravings from getting on the balls so that wear occurs.

In the drawing the space shown between 90 the upper and lower halves and between the various parts indicates merely a "working" fit but this space is shown greatly exaggerated for clearness.

From the foregoing it is obvious that my 95 invention is not restricted to the exact embodiment herein shown, but is broad enough to cover all structures coming within the scope of the annexed claims.

Having described my invention what I 100 claim is:

A device of the class described comprising an engraving block having an upper half and a lower half, a recess in one of said halves, a spindle on the other half extending 105 into said recess, the halves of the block each

having a depression, a ball bearing fitting said depressions and interposed between the halves of the block, said ball bearing having a central bushing through which the spindle 5 extends, shoulders on said bushing, a pair of plates surrounding the bushing, said plates holding the balls between them and

resting on said shoulders and openings in the plates through which the balls project to bear against the halves of the block. 10

Signed at the city of St. Paul, county of Ramsey, and State of Minnesota, this 27th day of April, 1917.

PERCY D. SHIRLEY.

Copies of this patent may be obtained for five cents each, by addressing the "Commissioner of Patents, Washington, D. C."
